S. S. MORTON,
LEVER LOCK,
APPLICATION FILED MAY 20, 1920.

1,382,529.

Patented June 21, 1921.

UNITED STATES PATENT OFFICE.

SAMUEL S. MORTON, OF HARRISBURG, PENNSYLVANIA.

LEVER-LOCK.

1,382,529.

Specification of Letters Patent. Patented June 21, 1921.

Application filed May 20, 1920. Serial No. 382,856.

To all whom it may concern:

Be it known that I, SAMUEL S. MORTON, a citizen of the United States, residing at Harrisburg, in the county of Dauphin and 5 State of Pennsylvania, have invented certain new and useful Improvements in Lever-Locks; and I do declare the following to be a full, clear, and exact description of the invention, such as will enable others skilled 10 in the art to which it appertains to make and use the same.

My invention relates to improvements in locking devices for levers or shafts having both pivotal and rotary movement, and the 15 present disclosure shows the invention in connection with a control shaft for a transmission mechanism such as that illustrated in my co-pending application, Serial No. 323,709, filed September 15, 1919. It is to 20 be understood, however, that the device may be used on numerous levers and the like in which it is necessary to normally hold them against either pivotal or rotary movement.

The principal object of the invention is to 25 provide an extremely simple and inexpensive, yet a highly efficient and reliable friction lock in which both pivotal and rotary movements of a control shaft or the like are normally prevented by the action of common spring means acting on friction shoes.

With the foregoing in view, the invention resides in the novel construction and arrangement of parts hereinafter described and claimed, the descriptive matter being 35 supplemented by the accompanying drawings.

Figure 1 is a side elevation partly in section.

Fig. 2 is a vertical section on the plane 40 indicated by line 2-2 of Fig. 1.

Fig. 3 is a horizontal section on the plane of line 3-3 of Fig. 1.

In the drawings above briefly described, the numeral 1 designates a transmission casting and 2 has reference to a vertical control shaft suitably mounted at 3 for both pivotal and rotary movement, the upper end of said shaft having a hand wheel 4 while its lower end is appropriately connected at 45 5 with the transmission mechanism, which mechanism forms no part of the present application, but is illustrated in detail in the application above referred to. It may be stated, however, that forward and rearward 55 swinging of the shaft 2 controls the direction of drive and the speed, while rotation

of said shaft effects steering. To hold the shaft 2 in any position at which it may be set, I employ the present invention, described specifically in the following. 60

A pair of arched bars 6 are suitably anchored at 7 on the casing 1 or on any other fixed support, with at least a portion of their lengths concentric with the joint 3, the shaft 2 being received between said bars so 65 that it may move either forwardly or rearwardly, but can have no pivotal movement transverse to said bars. A collar 8 is secured to the shaft 2 above the bars 6 and a friction shoe 9 is interposed between said 70 collar and bars, while a similar shoe 10 contacts with the lower sides of these bars, the two shoes 9 and 10 having central openings 11 through which the shaft 2 passes rather loosely. A collar 12 is secured on the shaft 75 2 below the shoe 10 and a coil spring 13 is interposed between said collar and shoe. This spring exerts a downward force on the shaft 2 and an upward thrust on the shoe 10 and it will thus be seen that not only will 80 the two shoes 9 and 10 be held in frictional contact with the bars 6, but the collar 8 is held in similar contact with the upper surface of the shoe 9. By this arrangement, pivotal movement of the shaft is resisted by 85 the action of the shoes 9 and 10 on the bars 6, while rotary movement of said shaft is normally prevented by the frictional contact of the parts 8 and 9. The friction between the several parts can be overcome whenever 90 the shaft 2 must be operated to control the transmission mechanism, but such friction is sufficiently strong to normally hold the shaft in any position at which it may be set.

Rotation of the shoes 9 and 10 with the 95 shaft 2 may be prevented by any preferred means, but I prefer that such means shall contact with the bars 6, and as typical of one form of construction which may be used for this purpose, I have shown a plurality of pins 14 carried by the shoe 9 and received rather loosely in openings 15 in the shoe 10. The pins 14 are positioned between and contact with the bars 6 and thus both of the shoes are held against rotation although 100 105 they are freely movable toward each other under the action of the spring 13.

Since probably the best results may be obtained from the details described, such details may be followed if desired, but I wish 110 it understood that within the scope of the invention as claimed, numerous minor

changes may be made. Furthermore, it is obvious that my invention may be used on shafts or levers of numerous types, whether they be employed for controlling transmission mechanisms or for other purposes.

I claim:

1. The combination with a shaft mounted for both rotary and pivotal movement; of a curved track extending transversely of said shaft, a friction brake movable along said track during the pivotal movement of said lever, a collar movable with said shaft when the latter is rotated, and spring means for engaging said collar with said friction brake and for holding the latter in frictional contact with said track.
2. The combination with a shaft having both pivotal and rotary movement; of a fixed curved track extending transversely of said shaft, a pair of friction shoes movable along said track during the pivotal movement of said shaft, a collar rotatable bodily with said shaft and contacting with one of said shoes, and spring means acting

in one direction against the other shoe and 25 in the opposite direction against said shaft, whereby to frictionally engage both shoes with the track and to frictionally retain said collar in contact with one of said shoes.

3. The combination with a shaft having 30 both rotary and pivotal movement, of curved tracks between which said shaft is movable, said tracks being concentric with the pivotal axis of the shaft, a pair of friction shoes contacting with opposite sides of 35 said tracks, said shoes having openings receiving said shaft and being provided with track engaging means holding them against rotation, a collar rotatable with said shaft and contacting with one of said shoes, and 40 a coil spring surrounding said shaft, said spring acting in one direction against the other shoe and in the opposite direction against said shaft.

In testimony whereof I have hereunto set 45 my hand.

SAMUEL S. MORTON.
